UNITED STATES PATENT OFFICE

158,399

COASTER TRIM ELEMENT

Isadore Albert Lipman, Meriden, Conn., assignor
to The Ellmore Silver Company, Inc., Meriden,
Conn., a corporation of Connecticut

Application March 9, 1949, Serial No. 1,313

Term of patent 14 years

(Cl. D44—10)

To all whom it may concern:

Be it known that I, Isadore Albert Lipman, a citizen of the United States, residing in Meriden, in the county of New Haven and State of Connecticut, have invented a new, original, and ornamental Design for a Coaster Trim Element, of which the following is a specification, reference being had to the accompanying drawing, forming part thereof, in which

Fig. 1 is a face view of a coaster trim element, showing my new design, and

Fig. 2 is a side elevational view thereof.

I claim:

The ornamental design for a coaster trim element, substantially as shown.

ISADORE ALBERT LIPMAN.
